US00D383681S

United States Patent [19]

Chiappetta et al.

[11] Patent Number: **Des. 383,681**[45] Date of Patent: ****Sep. 16, 1997**[54] **ELECTRONIC SPEED DETECTOR FOR
SPORTING ACTIVITIES**[76] Inventors: **John Chiappetta**, 62 Fieldcroft Court,
Maple, Ontario, Canada, L6A 1J3;
Mark John Francis, 303 Melita
Avenue, Toronto, Ontario, Canada, M6G
3X1[**] Term: **14 Years**[21] Appl. No.: **55,421**[22] Filed: **Jun. 5, 1996**[51] LOC (6) CL ..... **10-03**[52] U.S. Cl. **D10/40**; D10/96; D10/97;
D10/98[58] **Field of Search** D10/40, 41, 30,
D10/31, 37, 96, 97, 98; 368/107-113; 340/670;
324/160-180[56] **References Cited**
